UNITED STATES PATENT OFFICE.

JOHN L. SULLIVAN, OF BERKELEY, CALIFORNIA.

ANCHORING DEVICE FOR ROOFING TILE.

Application filed January 23, 1925. Serial No. 4,163.

My invention relates to means for anchoring roofing tile in proper position on a roof, and in its present embodiment is adapted for use in connection with Asiatic type of tile, particularly the imbrex member thereof.

An object of the invention is to provide a device which may be handled and applied as a unit to secure the imbrex tiles in position without necessitating the addition of special members to the roof structure.

Another object of the invention is to provide a device of the character described which may be readily applied to a tile and by the use of which the desired positioning of the tile will be assured.

A further object of the invention is to provide a device with the foregoing advantages which may be used for effectively securing the tile to the roof without danger of breaking the tile.

The invention possesses other objects and features of advantage, some of which, with the foregoing, will be set forth in the following description of the preferred forms of my invention which are illustrated in the drawings accompanying and forming part of the specification. It is to be understood that I do not limit myself to the showing made by the said drawings and description, as I may adopt variations of the preferred forms within the scope of my invention as set forth in the claims.

Referring to said drawings:

Figure 1 is a plan view of a portion of a tile roof showing the imbrex tiles held positioned by the devices of my invention.

Figure 2 is a fragmentary vertical section of the roof taken longitudinally through the imbrex tiles.

Figure 3 is a side view of one form of the device of my invention.

Figure 4 is a fragmentary perspective view of a slightly modified form of the tile engaging portion of the fastener.

Figure 5 is a view similar to Figure 2 showing the tiles secured in position by a slightly modified form of the device.

Figure 6 is a side view of the device shown in Figure 5.

Figures 7 and 8, and 9 and 10, are views similar to Figures 5 and 6, showing modified forms of the anchoring device.

Asiatic tiles include tegula and imbrex tiles. The former comprise the main tiles—usually of segmental section—which are laid on the roof surface in parallel rows with the edges of transversely aligned tiles spaced from each other. The imbrex tiles are arranged in rows over the tegula tiles in such manner that they will cover the space or "joint" between the adjoining rows of the tegula tiles. Each of the tiles is usually perforated adjacent the central portion of the forward edge so that a nail or other fastening device may be passed through the tile to fasten or anchor the same in position upon the roof surface. Since the perforated portion of the tegula tiles lays directly against the roof surface, no difficulty is encountered in securing these tiles to the roof, as a nail may be inserted in the perforation and driven into the roof. However, since the imbrex tile, particularly the perforated portion thereof, is positioned considerably above the roof surface, considerable difficulty has been met in effectively securing these tiles to the roof in a simple manner. Of the methods most commonly employed in anchoring such tiles to the roof, one is that of passing a wire through the perforation, forming a loop or coil thereof, and then securing one end of the loop to the roof by a nail. Another method is that of placing and securing wooden strips under the imbrex tiles in the space between the rows of tegula tiles, so that the imbrex tiles may be nailed to such strips in practically the same manner as the tegula tiles are nailed to the roof proper. The first mentioned of these methods is very slow and does not lend itself to the correct positioning of the tiles, while the latter method adds considerably to the cost of laying the tiles. In accordance, however, with my invention, the imbrex tiles may be effectively anchored in position without the disadvantageous features of the methods described.

As shown in Figures 1 and 2, in which a portion of the roof is illustrated, the tegula tiles 12 are disposed in overlapping relation and are laid directly upon the surface 13 of the roof structure 14. The tiles 12 are positioned in spaced rows and provided adjacent one end with perforations 16 into which

nails 17 or the like may be readily inserted and then driven into the roof to secure the tiles in position. Covering the spaces between the rows of tegula tiles, and arranged so that the opposite side edges 18 thereof will rest on such tiles, are the imbrex tiles 19 which in distinction to the first mentioned tiles, are disposed with their convex sides uppermost. Since the imbrex tiles are thus spaced from the roof surface, and the portions 20 thereof containing the perforations 16 are spaced further from such surface than are the sides 18, considerable distance is had between such holes and the surface 13 of the roof. It will thus be clear that to use an ordinary nail to secure the imbrex tiles to the roof, in the manner similar to that of securing the tegula tiles thereto, is impractical, and that for this reason other methods, such as those hereinbefore described, have been resorted to.

As illustrated in the drawings, I propose to use for securing the imbrex tiles to the roof, a device which is arranged to be handled and applied as a unit and which as shown in Figures 1 to 3, comprises a one-piece member 22 preferably formed of wire. The member 22 includes a tile-engaging-portion 23 and a roof-engaging-portion 24 which is disposed in offset relation to the first portion and connected thereto by an intermediate or shank portion 26. The tile-engaging-portion 23 as clearly shown in Figure 2, includes angularly disposed parts 28, 29 and 30 arranged to respectively lie over and under the tile and within the hole 16 thereof. With such portion 23 formed as illustrated in Figures 1 to 3, it is arranged to be placed in engagement with the tile by inserting the end portion 28 thereof upwardly through the hole 16. With the portion 30 lying within the hole, the portions 28 and 29 may be positioned to extend more or less parallel to and along the top and bottom surfaces of the tile thereby effectively locking the device to the tile, such locking feature being enhanced by the particular angular relation of the portions. The portions 28 and 29 in this embodiment extend in substantially opposite directions from the portion 30. In this manner the portion 28 may extend rearwardly along the top surface of the tile, while the portion 29 will then extend forwardly under the tile. The member 22, as above mentioned, is provided with a roof engaging portion 24 which in all of the forms herein illustrated comprises a prong angularly disposed with respect to the shank 26 and arranged to be driven directly into the roof structure. The shank 26 is preferably of such length that when the portion 23 properly engages a tile, the prong may lie well without the portion of the roof covered by said tile. In this way,

a minimum bending force will be exerted upon the shank, and the device, even though connected to the tile, may be readily struck to drive the prong into the roof without danger of breaking the tile. If desired, the portion 32 of the member at the juncture 70 of the shank and prong may be slightly offset to provide a more defined area for receiving the driving blow. It will now be evident that with the device of my invention, the imbrex tiles may be quickly and effectively anchored in position, without any of the drawbacks generally attending the use of the methods and devices heretofore employed.

To reduce the upward protrusion of the portion of the member arranged to lie along the top of the tile, such portion may be formed flat as shown at 38 in Figure 4.

In Figures 5 and 6, the tile engaging portion of the device is modified substantially to the extent that the tile-top engaging portion 48 extends from the hole-engaging-portion 50 in substantially the same direction as does the tile-bottom-engaging portion 49.

In Figures 7 and 8, the top and bottom tile-engaging-portions 58 and 59 of the device are reversed with respect to their positioning relative to the hole engaging portion 60, the device being arranged to be attached to the tile by insertion from the top of the tile hole.

The device as shown in Figures 9 and 10 is also arranged to be inserted from the top of the tile. As here illustrated, the tile-bottom engaging portion is practically dispensed with, the small portion 68 thereof being inclined toward the prong.

I claim:

1. In an anchoring device for an imbrex roofing tile provided with a perforation extending transversely through the body thereof, a shank, an angularly disposed prong at one end thereof arranged to be driven into the roof, and tile engaging means provided at the other end of said shank including a portion arranged to extend through said perforation and portions arranged to be disposed over and under said tile, one of said latter portions being arranged to be passed through said perforation, and all of said portions being coplanar with each other and with said shank and prong.

2. A roofing-tile one-piece anchoring device formed of relatively inflexible wire and adapted for use in connection with imbrex tiles having a perforation extending through the body thereof between the concave to the convex side, comprising a generally straight shank, tile engaging means at one end of said shank including a portion disposed at an obtuse angle to the axis of said shank and arranged to be disposed through said perforation in angular relation to the axis

thereof, and a portion contiguous with and disposed at an obtuse angle to said first portion and arranged to engage said upper side of the tile, said second portion being co-planar with the first but extending therefrom oppositely to the shank, and a prong formed at the other end of said shank arranged to

be driven downwardly into the roof at a point located without the area covered by the tile.

10

In testimony whereof, I have hereunto set my hand at Oakland, California, this 20 day of January, 1925.

JOHN L. SULLIVAN.
